UNITED STATES PATENT OFFICE.

EBER H. PATTON, OF LONGWOOD, MISSISSIPPI.

NUT-CRACKING MACHINE.

Application filed September 18, 1926. Serial No. 135,233.

The invention relates to improvements in nut-cracking machines one object is to crack pecans or other nuts leaving the kernel whole.

5 A further object is to produce a nut cracking device in which the crusher bar acts with a yielding pressure.

A further object is to produce a nut cracking device in which the crusher bar permits 10 of the cracking of a plurality of different sized nuts.

A further object is to provide a nut cracking device that is simple in construction, efficient in operation and readily assembled, adjusted and taken apart.

One embodiment of the invention is illustrated in the accompanying drawing, in which the figure shows a perspective view.

The device comprises a base frame or bar 20 1 which is provided at one end with a U-shaped clamp loop 1^a which is slipped over the edge of a table and held rigidly in place by the clamp screw 12. The opposite end of the base bar is provided with an upstanding 25 post provided at its upper end with perforated ears to which is hinged one end of the crusher bar 2, as by a bolt or rivet, the hinge joint being designated by reference numeral 3.

30 Projecting from the U-shaped loop is a lug or arm 10 which is provided with perforated spaced apart ears between which is pivoted the lower end of the operating handle 4. At a suitable distance from the joint 35 are a series of adjusting openings 11 within which the lower end of a link 5 is pivotally secured by suitable means, such as a bolt 6 or upsetting the end of 5 which may be extended through one of the openings 11.

40 The upper end of the link is also secured to the free end of the crusher bar as by a nut 7. An arcuate guide 8 extends upwardly from the bar or frame 1, its upper extending through a curved opening in the crusher 45 bar 2, keeping the crusher bar in line at all positions during the crushing or cracking operation.

A compression spring 9 surrounds the 50 guide post 8 between the base frame and the crusher bar. This spring 9 functions to hold the crusher bar to the normal inactive position, and closes during the operation of cracking but with a yielding pressure on the parts so that there is little or no danger of 55 the parts being broken.

As before stated, 11 are extra holes in operating handle 4, for the purpose of adjusting machine for longest nuts, by connecting 5 to 4, at 11 in place of 6, as shown in illustration. 13, 13, 13, are countersunk holes 60 for putting ends of nuts in to hold in position on frame 7 while cracking. There are also countersunk holes in bottom side of crusher-bar 2, indicated by dotted lines at 14, 15, 16, which correspond with 13, 13, 13, 65 enabling operator to use whichever set of holes is the right distance apart for different length pecans without adjusting the machine. 17, 18, 19, show the different places the pecans may be put in the machine. The 70 dotted lines show the position of pecan when in machine.

In operating the device the nut having been placed upright or longitudinally in the appropriate countersinks in the base frame and crusher bar, the upper end of handle 4 is forced outwardly and downwardly away from the machine, whereupon through the link 5, the crusher bar will be forced downwardly compressing spring 9 and cracking 80 the nut shell away from the kernel of the nut which is left whole or unbroken, the crusher bar having a yielding pressure. Upon releasing the handle the spring 9 expands and forces it up to inactive position, 85 whereupon the operation may be repeated.

By my novel construction and arrangement of parts I am able to produce a nut cracking machine that is simple, efficient and inexpensive to produce, the parts being removable and replaceable.

Having thus described my invention what I claim as new and desire to secure by Letters Patent is:

1. A nut cracking machine comprising in combination a base bar having a standard at one end, and a U-clamp at its opposite end, a crusher bar pivotally connected at one end to said standard, a perforated lug projecting from the clamp end of the base bar, a handle 95 pivotally connected at its lower end to said lug, said handle having a plurality of adjusting elements, a link pivotally connecting the free end of the crusher bar with the handle by said adjusting elements, said base bar and crusher bar provided with a plurality of opposing sockets to receive and longitudinally center various sized nuts, a guide post projecting upwardly from the base bar, 100 and through an opening in the crusher bar, 105 110

and a compression spring mounted on said guide post and between the base bar and crusher bar.

2. A nut cracking machine as defined in claim 1, the guide post being arcuate, and a compression spring being a coiled spring surrounding the guide post and bearing at

its upper and lower ends against the crusher bar and base bar respectively to force the crusher bar to inactive position, and to provide a yielding pressure during the nut cracking operation. 10
